UNITED STATES PATENT OFFICE

2,165,429

TYPE

Fritz Julius Weber, Winterthur, Switzerland, assignor to the firm Schweizerische Lokomotiv- und Maschinenfabrik, Winterthur, Switzerland

Application July 3, 1937, Serial No. 151,919
In Germany July 10, 1936

3 Claims. (Cl. 101—398)

This invention relates to patrices having classifier indentations within a V-shaped aperture.

The invention is for an improvement in and a modification of patrices of this kind for use in type line composing and printing machines and consists in the provision that the patrix body is provided with a longitudinal recess for receiving the type.

It is known, to connect type to patrix bodies of uniform thickness by riveting or casting. With type of relatively small thickness the material of the type left after considering the thickness of the patrix body becomes so thin that the type frequently break during the riveting or after the casting operation. Furthermore, it is easily possible that the type, when riveted on inclines slightly out of true position, due to the fact that the soft type metal inhibits clamping the type firmly.

In the patrix according to the present invention, the patrix body is provided at about the longitudinal axis thereof, thus at the portion contacting with the type, with a recess the depth of which corresponds about to half the thickness of the patrix body and the width of which is exactly equal to the lateral dimensions of the type. By this means, it is possible to cast the type in larger thicknesses and to guide each type properly, when riveted to the patrix body. Furthermore, such type are prevented from shifting out of position during use.

In the accompanying drawing several constructional examples of the invention are illustrated by way of example only, in which

Fig. 1 is a view of a patrix provided with a type which was cast thereonto;

Fig. 2 shows a side elevation of Fig. 1;

Fig. 3 is a cross section on the line III—III in Fig. 1;

Fig. 4 is a view of a type cast on to both sides of the patrix body;

Fig. 5 shows a side elevation of Fig. 4;

Fig. 6 is a cross section on the line VI—VI in Fig. 4, and

Fig. 7 is a cross section of a patrix provided with a type projecting on both sides beyond the patrix body.

The patrix body *p* has ears *a*, *b*, *c*, *d* for guiding the patrix, whilst the classifier indentations *z*¹, *z*² provided in the V-shaped aperture *V* serve for distributing the patrices to the guide passages of the magazine. The hole *l* and the incision *k* serve for classifying the various kinds of characters used, and in addition three holes are provided for the reception of plugs *f*. The type *t* is provided with an upper extension *e* which is arranged between the classifier indentations *z*¹, *z*² and carries the character image. The charac-

ter images on the type cast onto the body are produced by means of a mold *r* which can be applied for effecting type castings for use in type composing by hand.

In Fig. 1 this mold is shown to be removed. The recess *i* of the patrix body serves for receiving the type *t* for which it provides guidance in the transverse direction. The recess *i* further permits to cast the type onto both sides of the patrix body *p* so as not to project therefrom on one side (Fig. 6). Also for the type *t*, which projects on both sides beyond the patrix body *p* (Fig. 7), this recess provides increased staying in the transverse direction, so that the connecting plugs are relieved.

I do not limit myself to the particular size, shape, number or arrangement of parts as shown and described, all of which may be varied without going beyond the scope of my invention as shown, described and claimed.

What I claim is:

1. In a patrix having classifier indentations, a patrix body having a V-shaped aperture provided with classifier indentations on both shanks thereof, a type cast onto both sides of said patrix body, an extension provided on said type carrying the character image and being symmetrically disposed between said two shanks, and said patrix body being provided with a longitudinally extending recess for so receiving said type that said character image on said extension is situated beyond said classifier indentations.

2. In a patrix having classifier indentations, a patrix body having a V-shaped aperture provided with classifier indentations on both shanks thereof and also being provided with a longitudinally extending recess, a type having an extension carrying the character image and being mounted in said recess of the patrix symmetrically disposed between the two shanks thereof, whereby the thickness of the type is greater to the extent of the depth of the recess, and the strength of the type and the security of its attachment to the patrix are increased.

3. In a patrix having classifier indentations, a patrix having a V-shaped aperture provided with classifier indentations on both shanks thereof and also being provided with a longitudinally extending recess, a type having a width equal to the width of said recess and extending into said recess, an extension provided on said type carrying the character image and being symmetrically disposed between said two shanks, whereby the thickness of the type is greater by the depth of the recess in which it lies, and its strength and security of attachment to the patrix are increased.

FRITZ JULIUS WEBER.
